UNITED STATES PATENT OFFICE.

NORVAL CUNNINGHAM, OF PENNSBORO, WEST VIRGINIA.

ENVELOP-OPENER.

1,254,208.

Specification of Letters Patent. Patented Jan. 22, 1918.

Application filed December 14, 1915. Serial No. 66,841.

To all whom it may concern:

Be it known that I, NORVAL CUNNINGHAM, a citizen of the United States, residing at Pennsboro, in the county of Ritchie, State 5 of West Virginia, have invented certain new and useful Improvements in Envelop-Openers; and I do hereby declare the following to be a full, clear, and exact description of the invention, such as will enable others skilled 10 in the art to which it appertains to make and use the same.

This invention relates to improvements in envelop openers.

The principal object of the invention is to 15 provide a novel and efficient device of this character by means of which a quick and efficient shearing cut can be made along the edge of the envelop.

Another object is to provide a simple device 20 of this character which is compact in its structure so that it can be carried around in the pocket.

Other objects and advantages will be apparent from the following description when 25 taken in connection with the accompanying drawing.

In the drawing:

Figure 1 is an elevation of my improved envelop opener in normal or closed position;

30 Fig. 2 is a similar view showing the device in open position; and in connection with an envelop showing the use of the device;

Fig. 3 is a longitudinal sectional view of the device in the position of Fig. 1; and

35 Fig. 4 is a similar section in the position of Fig. 2.

Referring particularly to the accompanying drawing, 10 represents the side plates of the device which is in the form of a penknife. Secured between the side plates, at 40 one edge, and forming the back of the device is a longitudinally extending spring 11, one end of which bears on the pivotal end of a knife blade 12, disposed between the ends of 45 the plates. Pivoted between the other ends of the plates is a blade 13, the pivotal point of which is provided with a pair of lugs 14 and 15 spaced to form an intermediate notch

16. The face of the lug 15 is flat and is adapted to be engaged by the adjacent end 50 of the spring 11 to hold the blade in normal position between the plates. When the blade is moved outwardly the end of the spring snaps into the notch 16 and bears against the inner wall thereof which holds the blade in 55 partially open position. The remaining lug 14 engages against the end of the spring and prevents the further opening of the blade. The blade thus extends at an acute angle to the open or front side of the handle, and 60 when this blade is inserted under one end of the sealed flaps of an envelop and the device drawn along the envelop in parallel relation to the edge, the blade will sever the flap with a shearing cut. Thus the envelop can be 65 more quickly and effectively opened than with similar devices heretofore with which it is necessary to hold the same at the proper angle to produce the shearing cut. With the present device, the blade is held in such position with respect to the handle of the device 70 that no other action can be brought to bear on the envelop but a shearing, cutting action.

On the pivotal end of the blade 13, and 75 normally extending from the end of the handle of the device, whether the blade is in open or closed position, is an eye-member 17 which permits of the attachment of the device to a key ring or chain, and is used to 80 open the device with one hand only.

What is claimed is:

An envelop opener including a channeled handle member, a flat spring secured at its intermediate portion on the bottom of the 85 channel, a knife blade pivotally mounted in one end of the channel and movable into and out of the channel, the pivotal portion of the blade being formed with an inclined notch in the inner edge thereof for the reception of 90 the adjacent end of the spring at times, a lug on said blade outwardly of the notch for engagement with the end of the spring to hold the blade extended from the channel at an acute angle, said inner edge of the pivotal 95 portion of the blade being also formed with

a flattened face for engagement by the inner face of the adjacent end of the spring at times to hold the blade within the channel, and a fingerpiece on the pivotal portion of 5 the blade projecting beyond the end of the handle for moving the blade into and out of the channel.

In testimony whereof, I affix my signature, in the presence of two witnesses.

NORVAL CUNNINGHAM.
